UNITED STATES PATENT OFFICE.

CLARENCE W. WHITE, OF NORTH BENNINGTON, VERMONT.

DESIGN FOR A SEAT-BODY FOR CHILDREN'S VEHICLES.

52,814.

Specification for Design.

Patented Dec. 24, 1918.

Application filed March 8, 1916. Serial No. 82,934. Term of patent 14 years.

To all whom it may concern:

Be it known that I, CLARENCE W. WHITE, a citizen of the United States of America, residing in North Bennington, county of Bennington, and State of Vermont, have invented a new, original, and ornamental Design for a Seat-Body for Children's Vehicles, of which the following is a specification, reference being had to the accompanying drawing, forming part thereof.

Figure 1 is a side view of a seat body illustrating my new design, and

Copies of this patent may be obtained for five cents each, by addressing the "Commissioner of Patents, Washington, D. C."

Fig. 2 a top view thereof.

I claim:

The ornamental design for a seat body for children's vehicles as shown.

In testimony whereof I have signed this specification in the presence of two subscribing witnesses.

CLARENCE W. WHITE.

Witnesses:

IRVING COBB,
HARRIE C. WHITE.
